UNITED STATES PATENT OFFICE.

FRANK D. SHEPHERD, OF SALT LAKE CITY, UTAH.

INTERNAL-COMBUSTION ENGINE.

Application filed February 14, 1922. Serial No. 536,409.

To all whom it may concern:

Be it known that I, FRANK D. SHEPHERD, residing at Salt Lake City, county of Salt Lake, and State of Utah, a citizen of the United States, have invented certain new and useful Improvements in Internal-Combustion Engines, of which the following is a specification.

The object of my invention is to utilize to a higher degree than has heretofore been done, the energy or power of gasoline or like fuel in the operation of internal combustion engines. My invention consists in an internal combustion engine having the characteristics defined by or included within the meaning of the appended claims.

In the accompanying drawings:

Fig. 1 is a vertical section of an internal combustion engine embodying my invention in one form;

Fig. 2 is a top plan view of a portion of such engine;

Fig. 3 is a vertical section of a portion of a gasoline engine embodying another form of my invention;

Figs. 4 and 5 are similar views illustrating yet other forms of my invention.

Briefly described, my invention comprehends the utilization of a certain portion of hot gases resulting from the explosion of a charge in an engine to raise the temperature of a successive charge, and an important characteristic of my invention is the avoidance of any rarefaction or attenuation of the gases composing the fresh or incoming charge so that the latter when delivered into the cylinder has no less density than it has when coming from the carburetor. My invention may be embodied in diverse or varied forms, and is not dependent upon application to any particular type or style of engine, and hence, though I illustrate in the drawings various embodiments, and embodiments in engines of various construction, it is to be understood that the scope of my protection is not to be restricted only to what is illustrated. It will be found that each of the structures illustrated comprises a chamber or container so in communication with the combustion chamber of the engine that upon the compression stroke of the piston and upon ignition or explosion, some of the gas will be forced into such chamber, and upon the suction stroke it will flow out of such chamber back into the combustion chamber, and mingle or mix with the gas of

an incoming fresh charge, and, being in a heated condition, will raise the temperature of the fresh charge and thus promote greatly its efficiency. Since this mingling or mixture of the heated gases does not occur until the incoming fresh charge is in the cylinder, the gas has the same density it had on leaving the carburetor and undergoes no change in density such as occurs when a heated charge of gas is introduced into it between the carburetor and the cylinder, and the result is that the charge with my invention undergoes no loss of B T U and I get a high degree of compression from the conjoint action of the piston and the expansion effect of the heated gas thus added to the charge from the chamber or container, aforesaid. Preferably, I stop the supply of heated gas to the fresh charge when the engine attains a certain speed and its parts are heated up to a point where heat therefrom is sufficient to get a desired degree of efficiency from the gas, this stoppage being desirable, first because addition of heated gas is unnecessary, and second, to eliminate the danger of preignition.

Describing the engine shown in Figs. 1 and 2 first, 10, designates the cylinder, 11 the piston, 12 the head, (which is detachable), 13 the combustion chamber, and 14 the inlet valve thereof, such valve being lifted periodically from its seat by a cam-actuated stem, 15, as usual, and moved to and yieldingly held upon its seat by a coil spring, 16, in a container, 17, on the head, which acts upon the valve through a plunger or stem, 18, that extends from within the container where it has a spring engaged head, 19, and reaches to the valve, 14, passing from the container, 17, on the head, with a sliding fit through a guide hole, 20, in the head, 12, such valve seating means being similar to what appears in my prior patents, such as No. 1,236,991, August 14, 1915; No. 1,240,378, September 18, 1917; and No. 1,263,133, April 16, 1918.

Alongside the spring container, 17, is a chamber, 21, which is closed at the top in a gas tight manner by a cover plate, 22, that also closes in a gas tight manner the top of the spring container, 17, as by a gasket, 23, the interior of which chamber, 21, is in communication by a small bore tube, 24, with the combustion chamber, 13, adjacent the inlet valve.

It will be seen that on the compression

stroke of the piston, a small portion of the charge of gas confined in the cylinder, (the inlet valve being seated), will, as shown by arrows in Fig. 1, be forced into the chamber, 21, and on the explosion of the charge some of the hot, spent gases will be forced into said chamber, mixing with and heating the gas that may be therein, and upon the ensuing suction stroke of the piston since the gaseous contents of said chamber are under great pressure, much in excess of the pressure of the fresh, inflowing gas coming by the open inlet valve, such gaseous contents of the chamber, 21, will rush out of the latter into the inflowing stream of fresh gas, and by the inevitable swirling and eddying that is taking place, will thoroughly mix with and heat up the fresh charge. The continuation of this action depends on the relative speed of piston and rate of flow of the gas from the chamber, 21, and ceases when the speed of the piston is faster, and, hence, the length of the passage between chamber and cylinder determines this matter. It is for that reason that I employ the tube, 24, which extends above the chamber bottom to that height which, between successive strokes of the piston, will be too long at the determined speed of the piston for the gas to travel to the cylinder and under such conditions the gas will simply pulsate back and forth in the tube. Thus the interchange of gas between the chamber, 21, and cylinder is automatically controlled and involves nothing more than the length of the tube. If desired, a needle valve, 25, passed through a packed hole, 26, in the cover, 22, may be employed to regulate the size of the entrance at the top of the tube, 24, and thus the rate of flow in the tube nicely regulated. By removing such valve, access can be had to the interior of the tube through the hole, 26, in the cap for such cleaning as may be necessary. A drainage hole, 240, in the tube at the bottom of the chamber, 21, is provided for the outlet of any liquid condensation in the chamber.

Obviously the temperature of gases coming in contact with the tube, 24, will be raised because of the necessarily highly heated condition of the tube when the engine is in operation.

As shown best in Fig. 2, a single cap plate or cover, 22, is used for two adjacent spring containers, 17, and the gas-receiving chamber, 21, which is placed between them, a single bolt, 27, only being required to secure the cover, this arrangement making for economy, but while I regard it as desirable, I, of course, do not restrict myself to it.

The cylinder and head shown in Figs. 1 and 2 are water cooled, but if desired, as shown in Fig. 1, the water jacket may not extend over a portion of the combustion chamber wall so as to utilize the latter as a

hot plate to heat the gas in the cylinder. I prefer, however, to completely water jacket the spark plug, as shown in Fig. 1.

In the embodiment of my invention shown in Fig. 3, I do not have a separate chamber but utilize the spring container, 170, of the valve seating mechanism as the temporary receptacle for the gas or gases interchanging between the cylinder and such receptacle. In this case the space around the valve seating plunger or stem, 180, could be used for the gas flow first in one direction and then in the other, but, preferably, I provide one or more holes, 28, of small bore that extend from the cylinder to the bottom of the container, through which flow from the cylinder into the container is had, return flow therethrough being prevented by a check valve, 29, at the end of the hole in the container, the return passage of gas to the cylinder being provided for by making the plunger or stem, 180, tubular or hollow, the upper end of the passage, 30, thus provided being in communication with the interior of the container and the lower end in communication with the passage from the inlet valve into the cylinder. As the plunger or stem, 180, becomes highly heated, the gases passing through it are additionally heated by contact therewith, and by taking heat from said plunger or stem, they tend to lower the temperature thereof. The outlet from the passage, 30, is preferably formed by numerous small radial holes, 31, so that the hot gas issues therefrom in jets and as they are just above the inlet valve, they enter the incoming body of fresh gas as soon as it passes the open inlet valve, 140, and penetrate it in the form of small streams flowing in various directions and thus most advantageously act upon such gas. The gas flow is indicated by arrows in Fig. 3.

The check valve, 29, is a ball confined by a cage or guard, 32.

In Fig. 3 the cover of the container, 170, for the valve-seating spring, 160, is integral with the side walls, and the bottom of the container is a cylindrical block or plug, 33, screwed into a hole, 34, in the head, 120, of a size for inserting the spring, 160, the holes, 28, being in such plug.

In Fig. 4, I show my invention embodied in an engine not provided with the mechanism for seating the valve, 141, such as is shown in Figs. 1 and 3. In this case, the gas-receiving chamber, 210, is secured in a gas-tight manner in a hole, 340, in a head, 131, above the valve, 141, and a tube, 241, corresponding to the tube, 24, in Fig. 1 establishes communication between chamber and cylinder, 100, the tube having at its lower end small radial holes, 101, from which the hot gases issue in small jets into the incoming charge. The inlet valve is shown off its seat in Fig. 4 and the flow of gas from the

inlet manifold and the jets from the tube, 241, are shown by arrows. The tube, 241, has a drainage hole, 270. Preferably, the outer end of the chamber, 210, is closed gas tight by a removable cap, 35.

In Fig. 5, I show my invention embodied in an engine having a similar valve mechanism to that shown in Fig. 4, but the head, 132, in Fig. 5, is integral, whereas that shown in Fig. 4 is detachable, and the gas-receiving chamber, 211, in Fig. 5 is inserted in the hole, 341, in the head provided for assembling the inlet valve, 142, and which is usually closed by a solid plug. A plurality of gas transfer tubes, 242, of graduated length, are provided in Fig. 5 to cause the automatic stoppage of gas interchange at different speeds of the engine. Three such tubes are shown in Fig. 5. At the lowest 20 piston speeds, flow to all three back to the cylinder will take place, at a certain higher speed flow will only take place through the two shorter ones, at a still higher certain speed it will take place only through the shortest; and finally at still higher speeds it will cease through the shortest tube. A drainage hole, 271, is provided at the bottom of the chamber, and its top is closed gas tight by a removable cover, 350.

An important characteristic of my invention is the fact that since the spent hot gases follow the portion of fresh gas that enters the transfer tube, the first effect on the opening of the exhaust valves is the removal of 35 a portion at least of such spent gases through the exhaust, which, of course, have no fuel value, and whose presence in the fresh charge would simply deteriorate it, but before that removal takes place the heating effect thereof upon the valuable fuel gas in 40 the transfer chamber is obtained.

Tests of my invention show that with a given engine, increase of power, and less fuel is required and the engine will pull the 45 load at substantially slower speeds than in ordinary constructions and keep in balance.

In each of Figs. 1 and 3, the valve is shown as simply a disk or head not attached to the stem on either side; and in each of 50 Figs. 1 and 3, a lubricating device is shown in the form of a lubricant-holding bag suspended in the container so that its lower end is touched by the plunger head when it lifts with the valve and a certain quantity of 55 lubricant is wiped on to the cap, to descend therefrom into the plunger guide hole, the portion of the plunger adjacent the head is

reduced in diameter, and the coil spring, at its upper end is seated in a recess less in diameter than the interior of the container, 60 but none of these things nor the form of gas interchange means shown in Fig. 3 are specifically or particularly claimed herein, but all are so claimed in another application No. 537,025 filed February 16, 1922, excepting 65 such form of gas interchange means which specifically will be claimed in yet another application.

When in the following claims I use the term "cylinder," I do not thereby use that term in the narrow sense of merely that portion of the engine in which the piston reciprocates, but I use it as a matter of convenience to designate that portion of the engine generally which comprises the space 75 or chamber between the piston at any part of its stroke and the valves.

What I claim is:

1. An internal combustion engine having means to successively remove from and restore to the cylinder on the power-receiving side of the piston a part of the gaseous contents of the cylinder, said means comprising a chamber and a small bore tube extending into the chamber. 80

2. An internal combustion engine having means to successively remove from and restore to the cylinder on the power-receiving side of the piston a part of the gaseous contents of the cylinder, said means comprising a chamber and a small bore tube extending 90 into the chamber, and a valve device to control flow through said tube.

3. An internal combustion engine having means to successively remove from and restore to the cylinder on the power-receiving side of the piston a part of the gaseous contents of the cylinder, such means comprising a chamber in constant communication with the cylinder. 95

4. An internal combustion engine having means to successively remove from and restore to the cylinder on the power-receiving side of the piston a part of the gaseous contents of the cylinder, and means comprising a chamber that communicates with the cylinder, its place of communication with the cylinder being contiguous to the inlet valve, and such chamber being constantly in communication with the cylinder. 105

In testimony whereof I hereunto affix my signature.

FRANK D. SHEPHERD.
